RAIL ANCHOR

Filed Aug. 15, 1930

Charles T. Tiffany

UNITED STATES PATENT OFFICE

CHARLES T. HOFFMAN, OF WASHINGTON, DISTRICT OF COLUMBIA

RAIL ANCHOR

Application filed August 15, 1930. Serial No. 475,493.

This invention relates to rail anchors, and more particularly to an anchor of the type made of a single bar or strip stock.

A primary object of the invention is to provide a rail anchor of the character set forth having a rail flange gripping jaw and driving head positioned substantially in the plane of the rail base, whereby the driving head is readily adapted to receive a blow from a sledge or track maul for springing a hook at the opposite end of the anchor, over the rail flange opposite that engaged by the jaw. That is to say, the present construction aims to provide an anchor which conveniently provides for applying the necessary force for positioning the anchor on the rail in such a way that said force is not transmitted to a maximum degree directly to the part of the anchor which grips the rail flange. In anchors of the type heretofore used it is not only possible to overdrive the anchors on the rail flange but also the force of the blow is likely to cause rail fracture since the force of the blow is more or less directly transmitted to the rail flange due to the point or points of location thereon of the driving head or heads which may receive the blow of the applying force. However, with the present type of anchor the full force of the applying blow is transmitted directly to a resilient loop which constitutes an impact receiving head that not only distributes the applying force in an effective manner to the portion of the anchor forming the rail flange embracing jaw, but also, because of the relative leverages involved, transmits the applying force directly where it is most needed, namely, on the member having the hook which is intended to snap over the opposite rail flange and which is in line with the application of force so that the full effect of the applying blow is utilized to its maximum extent.

A further object of the invention is to provide a rail anchor including a rail flange embracing jaw which is spaced from the overhanging driving head portion of the anchor which continues downwardly and under the rail toward the opposite rail flange to provide the tie abutting part of the anchor. In that way the outermost part of the anchor constitut-

ing the driving head acts as a guard or shield to positively prevent direct transmission of the applying blow to the bend or bight constituting the outermost portion of the rail flange embracing jaw.

Another object of the invention is to provide a one piece spring steel rail anchor which may be readily applied and removed from the rail, thereby rendering the same capable of re-use without injury during the removal process and which will be equally effective in the re-used position because of the fact that during the initial application the metal of the anchor is never required to be subjected to its elastic limit or weakening distortion.

Other objects will appear as the description of the invention progresses.

In the accompanying drawings:—

Fig. 1 is a side elevation of the improved anchor applied to a rail.

Fig. 2 is an end elevation.

Fig. 3 is a side elevation of a modification of the invention utilizing strip stock instead of bar stock.

Fig. 4 is an end elevation of the anchor shown in Fig. 3 applied.

I am aware that rail anchors consisting of a single piece of material comprising a double resilient jaw portion forming an overlapping double leaf spring, and an upwardly extended portion at its other end connected by a depending intermediate portion are old, but these anchors are placed or driven home by a force delivered to such intermediate depending portion for the purpose of applying the same to the rail. Furthermore, the overlapping portions of such anchors are of the same contour and are in substantial contact with each other which does not provide the effect sought to be obtained by the present invention, wherein the rail flange embracing jaw is spaced from the overhanging driving head portion in such a way as to stand free thereof to provide ample driving tolerance to insure the delivery of the full force of the applying blow to the tie abutting portion having the hook to be snapped over the other rail flange.

In that connection a distinctive feature of the present anchor is that the point of applica-

90

95

100

tion of the applying blow is located outside and away from a vertical plane intersecting the outermost face of the rail flange, thus placing the point of blow impact well beyond the limits of the rail to facilitate its striking by the sledge or maul. Heretofore in anchors of the type having a resilient striking head it has been the general practice to locate the same beneath the bottom of the rail flange, which is undesirable because of ballast interference and rail flange interference with the handle of the sledge or maul.

Referring to the drawings, A designates the present anchor in its entirety while B designates the base of the rail having the flanges B1 and B2.

The body of the anchor A may be made of bar stock, that is, substantially square material, or it may be made of strip stock wherein one dimension is greater than the other. In either event the stock is of spring steel of the type usually employed in the construction of rail anchors.

The body of the rail anchor A in Fig. 1 includes a rail flange embracing jaw C consisting of the members 1 and 2 connected by a bend 3, and the upper arm 2 of the jaw is provided with a reverse bend 4 that is continued to provide a lever L which includes an outwardly and downwardly extending resilient striking head 5 which substantially encircles the jaw but stands free therefrom so that the metal at the bend 4 serves as a fulcrum or hinge when the force of the applying blow is delivered to the head 5 in the direction of the arrows. The driving head 5 is continued as at 6 to provide a tie abutting portion lying beneath the rail base B, the same being preferably of relatively straight formation as shown in Fig. 1, and having its free end turned upwardly as indicated at 7 to provide a rail flange engaging hook.

It is also pointed out that the jaw 1-2-3 and the hook 7 constitute rail flange engaging abutments for gripping the opposite base flanges of the rail, and these rail flange engaging abutments are in turn connected by the tie abutting member 6.

The initial position of the anchor on the rail is shown in dotted lines in Fig. 1, from which it will be observed that when the arms 1 and 2 of the jaw are in their initial outwardly advanced position, the surface 8 of the hook 7 engages the bottom face of the rail. Thus the anchor in its initial position on the rail may be held steady so that the application of the blow of the applying force on the head 5 will readily snap the hook 7 to the full line position shown in Fig. 1.

The bend 4 connecting the jaw with the jaw encircling loop 5 and depending member 6 constitutes a lever which is essentially parallel to the vertical axis of the rail web. As the rail to which the anchor is attached tends to creep and the depending member is in con-

sequence pressed against the tie, a pronounced leverage action is produced to distort the jaw, causing it to bite into the rail flange on both its upper and under surfaces, accompanied by an urging of the bight of the jaw against the edges of the base flange of the rail due to the simultaneous twist of the bend 4 lever in a direction clockwise of the forward or creeping direction of the rail. These features produce great tenacity in the anchor to resist slipping of the rail base through the jaw with consequent increased efficiency.

Another advantage of the construction shown herein is that the part 4-5-6 is always maintained in compression after the anchor is once applied to the rail. In anchors have substantially U-shaped loops located beneath the rail base there is a tendency of the loop to spread and the elasticity of the metal gradually declines due to the fact that the loop is pulled apart to effect application to the rail base, while in the present construction the part 4-5-6 is pulled to a closed increased gripping position. In anchors having a depending spring loop the gripping force depends entirely upon the resistance of the arms of the loop to the gripping force. In the present construction, however, the resilient loop 4-5-6 is compressed or contracted since the point where the stress is focused is located above the plane of the rail base instead of below. In other words, the outstanding resilient loop 5-6 has a tendency when applied to the rail to urge the jaw 1-2-3 toward the hook 7 due to the contraction of the loop 5-6, thus forcing the anchor to grip the rail with increasing effectiveness.

Due to the novel construction utilized in the present anchors, the force to apply the anchor to its operative position on the railroad rail may be delivered not only in the immediate zone of the plane of the rail base, but with equal effectiveness may be delivered on the portion of the jaw-overlying-loop or driving head below the point of intersection of a line representing the plane of the bottom surface of the rail base and a line parallel to the vertical axis of the rail located at the outer face of the loop. Should applying blows be delivered on the driving head below said point of intersection, the body of the anchor will be flexed upward in effecting placement of the anchor in operative position on the rail.

It will also be clear from Fig. 1 and Fig. 3 that a blow delivered on the loop, either in the plane of the rail base or below such plane, will seat the rail flange embracing jaw portion 1-2-3 in gripping position on the rail flange by causing such jaw portion to turn in the arc of a circle as it proceeds on the flange, thus expanding the loop until such expansion is overcome by the required force to place such loop under sufficient compression to permit or force the rail flange engag-

ing hook to seat in its operative position on the rail flange opposite that engaged by the jaw. That is, the loop is expanded to a certain degree due to the angular initial engagement of the jaw with the edge of the rail flange and the required turning of the jaw when proceeding on the flange, while the end 8 of the hook 7 rides in a horizontal plane on the bottom face of the rail as shown by the dotted lines in Fig. 1.

The disposition of the tie abutting portion of the present anchors is such that approximately one-half of such tie abutting portion is located on each side of a vertical plane intersecting the junction of the bend 4 lever and the jaw portion 1—2—3 when the anchor is in operative position on the rail, as is clearly shown in Fig. 1. This construction distributes the tie abutting stress on the anchor so as to maintain the anchor in substantial balance in relation to the grip of the jaw on the rail flange engaged thereby, with consequent substantial elimination of the tendency of the hook to skew out of line with the cross tie which abuts the anchor. In other words, the anchor is thus held evenly against the tie with relation to that part of the anchor, the jaw, which maintains the principal anticreeping grip on the rail. This is not true of anchors whose intermediate tie abutting portion unequally abuts the tie in relation to the effective rail gripping means.

A further novel feature of the present construction resides in the formation of the loop 35 5 about the jaw 1—2—3 in such a way that the outer face of the loop which constitutes the driving head and also the part 6 connected therewith may be struck at various tangential points above and below or in line with the rail base to effect the application of the anchor. That is to say, the portion 5 is of looped, U-shaped, or compound curve formation thereby presenting a plurality of impact or blow receiving points radial to imaginary centers located within the jaw 1—2—3, so that when the portion 5 is struck anywhere along its outer accessible face the force of the applying blow will move the part of the driving head thus subjected to tangential stress in 40 the direction of the respective radius to compress the loop and its associated part 6 to snap the hook 7 over the opposite rail flange, with the coincident placement of the jaw 1—2—3 on the flange to be engaged thereby.

55 A modification of the invention is shown in Fig. 3 wherein strip stock is used. If, for example, a bar $\frac{1}{2}$ " by $\frac{3}{4}$ " is used, the arms 1a and 2a of the jaw may be formed so that the $\frac{1}{2}$ " or shorter dimension of the bar may bear on the upper and under surface of the base flange of the rail. The metal of the anchor is then turned or twisted as indicated at 9 at a point between the outermost limit 60 of the driving head 5a and the bend 4a. The

width of the jaw will thus be rendered less transversely of its longitudinal dimension than the width of the depending member parallel to the rail base, with the resulting submergence of the jaw within the indicated limits of the tie abutting portion. The result will be that the tie abutting portion 6a of the anchor will independently bear against the tie without any contact of the jaw with the tie. This is a distinctive and important feature, in that the under portion of the jaw will in this manner be prevented from injuring the edge of the tie due to the vibratory action of the rail under passing wheel loads accompanied by tendency of the rail to creep and carry the jaw portion against the tie. Moreover, the submergence of the jaw within the cross-sectional limits of the tie abutting portion 6a of the anchor is accomplished by this method without the need for providing anchors of rights and lefts construction. While this serves to cause the narrower side of the bar to bear against the tie, the longitudinal dimension of the depending member is more than sufficient to offset the cross-sectional difference without the need for bends or loops in the tie abutting portion.

It will, of course, be understood that the present invention contemplates the turning or twisting of the strip stock at any point of the anchor in proximity of the jaw or within the jaw itself, as the purpose of this feature of the invention will be achieved so long as the turn or twist occurs above the plane of the bottom surface of the rail base.

I claim:

1. A one piece rail anchor including a rail flange engaging jaw and a rail flange engaging hook and an intermediate driving head standing free of the jaw and located in the plane of the rail base.

2. A one piece rail anchor including a rail flange engaging jaw and rail flange engaging hook and an intermediate driving head located in the plane of the rail base, and lying outside of a vertical plane intersecting the outer edge of the jaw.

3. A one piece rail anchor including a rail flange engaging jaw and a rail flange engaging hook connected by a spring lever bent around and standing free of the jaw to provide a driving head located substantially in the plane of the rail flange embraced by the jaw, and the portion between the driving head and the hook constituting a tie abutting portion.

4. A one piece rail anchor including a jaw and a resilient attaching lever spaced from the jaw to provide driving tolerance for snapping a hook formed at the end of the lever over the rail flange opposite the one engaged by the jaw.

5. A rail anchor including a rail flange embracing jaw and a lever connected with the jaw at the upper side of the rail flange em-

bracing portion and continuing outwardly and downwardly around the jaw to provide a striking head and tie abutting portion, and a locking hook formed on the free end of the lever.

5 6. A one piece rail anchor including a rail flange engaging jaw and a hook connected by a spring loop standing free of the jaw and constituting a lever whose fulcrum is located 10 at the junction of the loop with the jaw whereby when the loop is struck substantially in the zone of the plane of the rail base the force of the blow will be transmitted indirectly to the jaw and directly to the portion of 15 the loop terminating in the hook.

7. A one piece rail anchor including a rail flange engaging jaw and a hook connected by an intermediate loop constituting a driving head and overlying and spaced from the 20 jaw to constitute a blow impact receiving point for transmitting the force of the applying blow to the portion of the loop adapted to lie beneath the rail.

8. A one piece rail anchor formed to provide a rail flange gripping jaw and the part 25 of the anchor joined with the upper part of the jaw being coiled about and spaced from the jaw to extend beneath the rail base, and a hook formed on the free end of said coiled 30 portion to engage the rail flange opposite the one engaged by the jaw whereby when the anchor is applied to the rail the coil is compressed to urge the jaw on the rail flange.

9. A one piece rail anchor comprising a 35 body having a rail flange engaging hook at one end, and the end of the body opposite the hook being formed with a rail flange engaging jaw nested within a coiled portion of the body whereby when the anchor is applied to the rail the jaw and coiled portion 40 are forced toward each other.

10. A one piece rail anchor comprising a body of loop formation having a hook formed at one end for engaging with a rail flange 45 and a striking head formed at the side opposite the hook, and a rail flange embracing jaw formed at the inner end of the body and spaced from the striking head whereby the force of the applying blow applied to the 50 striking head will yieldingly urge the jaw on the rail flange.

11. A one piece rail anchor made of bar stock one of whose cross-sectional dimensions is greater than the other, a jaw formed from 55 a part of the metal of least width in the plane of the rail base and the metal of the bar stock being twisted in the direction of its axis adjacent the jaw whereby the metal of the stock of greatest width in the plane 60 of the rail base may be continued around the jaw to form a striking head, and thence extended to form a tie abutting portion, and a hook formed on the end of the tie abutting portion.

12. A one piece rail anchor made of bar

stock one of whose cross-sectional dimensions is greater than the other, a jaw formed at one end of the bar and the metal of the bar adjacent the jaw being twisted about its longitudinal axis and continued downwardly and outwardly about the jaw and thence forwardly to form a tie abutting portion having a hook, the width of the metal in the jaw being less than the width of the continued portion of the bar whereby the jaw 75 is submerged in relation to the tie abutting portion.

13. A spring one piece rail anchor formed to provide a rail flange engaging jaw, a striking head in shielding relation to the jaw 80 and a tie abutting portion, said striking head and tie abutting portion having their outer faces lying in planes beyond the planes of the faces of the jaw, and a hook formed on the free end of the tie abutting portion.

14. A spring one piece rail anchor formed with a jaw and a tie abutting portion, said jaw being of less width than the tie abutting portion whereby the jaw cannot come into tie abutting engagement.

15. A spring one piece rail anchor formed to provide a rail flange embracing jaw and a hook connected by a compression spring loop, said loop projecting beyond the outward limits of the jaw to provide a driving head.

16. A rail anchor comprising a body formed at one end with a jaw portion for engaging the rail flange and formed at the other end with a rail flange engaging hook, the jaw and the hook being connected by an intermediate portion adapted to be flexed upward to apply the anchor to the rail.

17. A one piece rail anchor including a rail flange engaging jaw and a hook connected by an intermediate loop, said loop being 205 adapted to be flexed toward the jaw to apply the anchor to the rail.

18. A one piece rail anchor including a rail flange embracing jaw and a rail flange engaging hook connected by an intermediate lever, said lever being fulcrumed at the top of the jaw.

19. A one piece rail anchor including a rail flange engaging jaw and a hook connected by an intermediate lever, said lever being fulcrumed at the junction of the lever with the upper side of the jaw.

20. A one piece rail anchor including a rail flange engaging jaw and a hook connected by an intermediate loop, said loop being adapted 120 to be expanded above the rail base to apply the jaw to the rail flange engaged thereby.

21. A one piece rail anchor including a rail flange engaging jaw and a hook connected by an intermediate loop, said loop being adapted to be expanded above the rail base to apply the jaw to the rail flange engaged thereby and to be compressed to apply the hook to the rail flange opposite that engaged by the jaw.

22. A one piece rail anchor including a rail flange engaging jaw and a hook connected by an intermediate loop, said loop being adapted to be alternately expanded and compressed to apply the anchor to the rail. 5
23. A one piece rail anchor including a rail flange engaging jaw and a hook connected by an intermediate loop, said loop being adapted to be alternately expanded and contracted 10 around the jaw to apply the anchor to the rail. 70
24. A one piece rail anchor comprising a rail flange embracing jaw and a hook connected by an intermediate tie abutting portion, said tie abutting portion standing free of the jaw below the rail base and being adapted to maintain the applied anchor in substantial balance when engaged by the tie. 15 75
25. A one piece rail anchor comprising a rail flange embracing jaw and a hook connected by an intermediate member including a portion adapted to underlie the base of the rail and a portion constituting a striking head disposed beyond the jaw and also lying 20 at one side of the base of the rail. 80
26. A one piece rail anchor comprising a pair of rail flange engaging members connected by a body member a portion of which stands free of one of the rail flange engaging 25 members, whereby such rail flange engaging member may be moved with reference to the other rail flange engaging member to place the anchor under compression. 85
27. A one piece rail anchor comprising a rail flange embracing jaw and a hook connected by an intermediate tie abutting portion standing free of the jaw, said jaw being adapted to be applied to the rail flange by tangential stress imposed on the part of said 30 tie abutting portion standing free of the jaw. 90
28. A one piece rail anchor including a hook and a jaw connected by a spring loop standing free of the jaw, whereby said jaw and hook are closer together before application 35 to the rail than when applied, thereby 95 to place the spring loop under compression.
29. A rail anchor comprising a body of spring strip stock of substantially spiral formation, a hook formed at one end of the spiral formation for engaging one flange of the rail, and a jaw formed at the other end of the spiral formation and lying within the same for engaging the other flange of the rail. 100
30. A rail anchor comprising a body formed of a piece of spring strip stock, said body being of substantially U-shaped formation, a hook formed at one end of the U-shaped portion, and a rail flange embracing jaw within the U-shaped portion and yielding 105 connected with the other end of said U-shaped portion. 105
31. A rail anchor made from spring strip stock including a spring rail flange embrac- 110
- ing jaw and a spring loop connected with the upper arm of the jaw and having a hook at its free end whereby when the anchor is applied to the rail the spring jaw will be forced on to the rail flange and the pressure of the spring loop will be applied to said upper arm of the jaw. 115
32. A rail anchor including a spring rail flange embracing jaw and a hook connected to said jaw by a compressible spring member extending around the outer side of the jaw and urging the jaw toward the hook when the anchor is applied to the rail. 120
33. A rail anchor including a rail flange embracing jaw and a hook connected by a creep-resisting member extending around the jaw and connected with the upper surface thereof whereby the component force due to the clockwise movement of the jaw by said member in resisting creeping movement of the rail will cause said jaw to tightly grip the rail flange by relative twisting movement. 125
34. A rail anchor including a rail flange embracing jaw and a hook connected by a creep-resisting member, said member being connected to the jaw by a bend extending upward from the jaw, and the intermediate portion of said member being looped about the jaw. 130
35. A rail anchor including a rail flange embracing jaw and a hook connected by a creep-resisting member, said creep-resisting member being joined with the jaw by a bend constituting a lever whereby movement of the creep-resisting member will cause said lever to urge the bight of the jaw against the base flange of the rail due to the simultaneous twisting of the lever in a direction clockwise of the forward or creeping direction of the rail. 135
36. A rail anchor made of a single piece of spring steel formed at one end with a rail flange embracing jaw and at its opposite end with a rail flange engaging hook, said jaw and hook being connected by a resilient spring loop substantially encircling but standing in shielding relation to the jaw and forming a rail underlying tie abutting portion intermediate the jaw and the hook. 140
37. A one piece rail anchor including a rail flange engaging jaw and a rail flange engaging hook connected by a spring loop overlying but spaced from the jaw and constituting a tie abutting portion and a driving head located substantially in the plane of the rail base. 145
38. A one piece rail anchor adapted for lateral application to a rail base including a jaw adapted to engage with the upper and lower faces of one flange of the rail and an abutment for engaging the edge of the opposite rail flange, said jaw and abutment being connected by a substantially straight un- 150

- der rail portion and a loop, said loop being adapted to be compressed by a blow or equivalent stress to place the jaw and abutments in operative position on a rail.
39. A rail anchor adapted to be applied laterally to a rail base including a body formed to provide a rail flange embracing jaw and a driving head spaced therefrom in a substantially horizontal plane and having an arm portion extending beneath the rail base toward the other rail flange, and means on the end of said arm portion for engaging with the opposite rail flange.
40. A one piece rail anchor comprising a rail flange embracing jaw and a rail flange engaging abutment connected by an intermediate creep-resisting tie engaging portion, said tie engaging portion being disposed so as to provide substantially equal tie engaging areas at each side of a vertical plane intersecting the junction of the intermediate portion with the jaw.
41. A rail anchor including a rail flange embracing jaw and a rail flange engaging hook connected by an intermediate portion, the portion of the jaw underlying the rail being of less width than the intermediate connecting portion whereby the jaw cannot come into tie engagement.
42. A rail anchor including a body having a rail flange engaging jaw and a hook, and said body between the jaw and hook being formed with a tie engaging loop standing free of the jaw below the rail base, the outer side of the bend of the loop being disposed as a driving head lying beyond the edge of the rail flange.
43. A rail anchor made from a single piece of strip material including a jaw and a hook for engaging the opposite base flanges of a rail connected by a compression creep-resisting tie abutting member; said tie abutting member, below the plane of the underside of the rail base, being disposed for full engagement with the tie throughout the length of said member.
44. A rail anchor adapted to be laterally applied to a rail, including a jaw adapted for initial rail flange engagement and a hook adapted for subsequent locking engagement with the other flange of the rail, said jaw and hook being connected by a creep-resisting member including a striking head standing free of the initial rail flange engaging jaw and located at the end of the anchor having the initial rail flange engaging jaw.
45. A rail anchor including a body having a jaw and hook, and said body between said jaw and hook being formed with an under rail creep-resisting member including a striking head disposed at an outwardly advanced location with reference to the jaw and standing free thereof below the rail base.
46. A rail anchor made of a single piece of material and including spaced rail flange engaging parts connected by an impact receiving member whereby the effect of a blow on the impact receiving member is to compress the same with reference to the said rail flange engaging parts to lock the anchor to the rail.
47. A one piece rail anchor including a body having a rail flange embracing jaw and a locking hook connected by a tie abutting member, a portion of said tie abutting member being formed to provide a driving head which when subjected to pressure is thereby compressed to move the locking hook into engagement with the rail flange.
48. A one piece rail anchor including a body having a rail flange embracing jaw and a locking hook connected by a compression tie abutting member, said tie abutting member being formed with a driving head, whereby the pressure of a blow on the driving head will cause the seating of the jaw on one rail flange and the engagement of the hook with the other.
49. A rail anchor including a body having a pair of rail flange engaging abutments, and said body between said abutments being adapted to be compressed by an applying blow delivered thereto whereby to place both abutments in operative position on a rail.
50. A rail anchor comprising a body including a pair of rail flange engaging abutments, the part of the body connecting said abutments having a substantially straight under rail portion connected with one of said abutments by a loop adapted to be compressed by a blow or equivalent stress to place both abutments in operative position on a rail.
51. A rail anchor comprising a body including a pair of rail flange engaging abutments, the part of the body connecting said abutments having a relatively straight under rail portion connected with one of said abutments by a loop presenting a plurality of impact receiving points whereby the loop may be compressed by a blow or equivalent stress to place one of said abutments in operative position on one rail flange with the coincident placement of the other abutment on the opposite rail flange.
52. A rail anchor comprising a body including a jaw and a hook, the part of the body connecting said jaw and hook being of substantially straight formation beneath the rail and the straight formation being connected with said jaw by a loop adapted to receive a blow or equivalent stress whereby to place both the jaw and the hook in operative position on a rail.
53. A one piece rail anchor comprising a body of loop formation having a hook formed at one end for engaging with a rail flange and a striking head formed at the side opposite the hook, and a rail flange embracing jaw

formed at the other end of the body and spaced from the striking head whereby the force of an applying blow delivered on the striking head will place the jaw and the hook in operative position on a rail.

5 In testimony whereof I affix my signature.

CHARLES T. HOFFMAN.
